No. 797,540.

PATENTED AUG. 15, 1905.

A. C. URBAN.

AUTOMATIC DOOR OPERATING DEVICE.

APPLICATION FILED SEPT. 17, 1904.

UNITED STATES PATENT OFFICE.

ALFRED C. URBAN, OF BUXTON, IOWA, ASSIGNOR OF ONE-HALF TO
NATHAN P. HERRINGTON AND ONE-FOURTH TO ERIC F. BROWN,
OF BUXTON, IOWA.

AUTOMATIC DOOR-OPERATING DEVICE.

No. 797,540.

Specification of Letters Patent.

Patented Aug. 15, 1905.

Application filed September 17, 1904. Serial No. 224,927.

To all whom it may concern:

Be it known that I, ALFRED C. URBAN, a citizen of the United States, residing at Buxton, in the county of Monroe and State of Iowa, have invented certain new and useful Improvements in Automatic Door-Opening Devices, of which the following is a specification, reference being had therein to the accompanying drawings.

It is customary to provide the passage-ways or galleries of mines with heavy doors by which they are divided into sections for controlling the air or ventilation or for other purposes, and such doors must of course be opened and closed at proper times when the cars carrying the products of the mines are to pass by the partitions of the passage-ways or galleries afforded by such doors.

The object of this invention is to provide a simple and efficient mechanism by which these partitioning - doors may be automatically opened, locked in opened positions during the passage of the cars therethrough, and then be automatically closed after the cars have passed.

In the accompanying drawings, Figure 1 is a plan view representing a section of a horizontal passage-way or gallery of a mine provided with doors to be opened and closed, together with the present improved automatic mechanism for effecting these operations. Fig. 2 is a detail perspective view of a frame for locking the doors in open positions. Fig. 3 is a detail perspective view of that portion of the door-opening mechanism which is to be operated by an approaching car. Figs. 4 and 5 are detail elevations showing the door opening and locking mechanism in connection with a car-truck. Figs. 6 and 7 are detail views of the slotted plates forming the parts of the connecting-rods joining the opening mechanism to the doors.

Referring to the drawings, 12 13 denote heavy doors suitably hung in a gallery or passage-way of a mine and which when closed serve as a partition in such passage-way or gallery, the latter being provided with railway-tracks 14 for the trucks of cars 15. At one side of the passage-way in the mine is arranged a vertical rock-shaft 16, which may be journaled in any suitable manner, as by means of the yoke or frame 17 and a suitable base 18. The shaft 16 is provided with a long arm

19, the outer or free end of which extends into the path of movement of the body of a car 15, as denoted in Figs. 1 and 4, so that a car approaching in the direction denoted by the arrow 1 in Fig. 1 will strike the said arm. The rock-shaft 16 is provided with a lower arm 20, joined by a connecting-rod 21 and a spring 22 to one arm of a lever 23, the other arm of which is connected by a link or rod 24 with the door 12 through a pin 25 on a plate or bottom piece 38, attached to the door 12. The end of the rod 24 adjacent to the door 12 is slotted where it engages the pin 25 for a purpose which will presently appear. The door 12 is connected by a link 26 with an arm 27 on the door 13, so that when the door 12 is opened and closed corresponding movements will be imparted to said door 13.

Mounted adjacent to one of the rails 14 is a rocking frame comprising a longitudinal bar 28, having curved end portions, and a series of arms 29, connecting said bar with a rod 30, which is mounted in brackets 31, suitably fixed to the floor of the passage-way or gallery. The bar 28 is of a suitable height to be engaged by the hub of a car-truck 32, so that after the body of an approaching car has engaged the arm 19 of the door-opening device and swung the doors open, as denoted by the curved dotted lines in Fig. 1, the hub of the car-truck will engage said bar 28 and tilt the locking-frame from the position shown in Fig. 4 to the position shown in Fig. 5, thereby bringing a projection 33 on one of the arms 29 behind the end of the arm 20 of the rock-shaft 16, so as to lock the doors in opened positions while the car or train of cars is passing through the open door, the hubs of the successive trucks of the car or train of cars continuing to engage the locking-bar 28 while the train is passing. After the car or train of cars has passed through the open doors the latter will be automatically closed by any suitable means, as by a spring or springs 34, or, if desired, by suitable weights in a well-known manner.

For the purpose of opening the doors 12 13 when a car or train of cars is moving in the direction opposite that denoted by the arrow 1 in Fig. 1 the opening device, comprising the rock-shaft 16, with its arms 19 and 20, as also the rocking frame 28, with its appurtenances, are duplicated at the other side of the

doors, and in this instance the lower arm 20 of the opening device is connected with the door 12 by means of a two-part rod 35, preferably having a stiff pushing-spring or yielding connection at 36. In other words, the mechanism last referred to for opening the doors when a car is approaching in the direction denoted by the arrow 2 in Fig. 1 will be substantially a duplicate of the mechanism first described with the lever 23 omitted.

The yielding connection between the arm 20 of the rock-shaft 16 and the doors to be opened afforded by the spring 22 serves to cushion the shock or jar which would otherwise result when an approaching car strikes the arm 19 of the said rock-shaft. Also the yielding connection between the two parts of the rod 35 afforded by the cushioning-spring at 36 serves to cushion the jar or shock which would otherwise occur when a car is approaching in the opposite direction.

The slotted portions of the rods 24 and 35 entered by the pin 25 on the bottom piece 38 of the door 12 permit either of the door-opening mechanisms arranged at the opposite sides of the doors to be operated without imparting movements to or affecting the other door-opening mechanism and also permitting the doors to be opened by hand without affecting or moving either of the said door-opening mechanisms.

Having thus described my invention, I claim and desire to secure by Letters Patent—

1. A door-opening mechanism for mines and the like, to be automatically operated by an approaching car or train, consisting of the combination with a door, of a vertical rock-shaft located at one side of the car-track and provided with an arm to be engaged by an approaching car, suitable connections between said rock-shaft and said door whereby the latter will be opened when the said arm is swung aside by the approaching car, a locking device, independent of the opening device and engaged by the car, said locking device serving to hold the door in opened position while the car or train of cars is passing, and a second door connected with and operated by said first-named door.

2. A door-opening mechanism for mines and the like, to be automatically operated by an approaching car or train, consisting of the combination with a door, of a vertical rock-shaft located at one side of the car-track and provided with an arm to be engaged by an approaching car, suitable connections between said rock-shaft and said door whereby the lat-

ter will be opened when the said arm is swung aside by the approaching car, a locking device independent of the opening device and operated by the car, said locking device serving to hold the door in opened position while the car or train of cars is passing and comprising an oscillating frame having an arm or projection to be engaged by hubs or parts of the car-trucks, and a second door connected with and operated by said first-named door.

3. An automatic door-opening mechanism for mines and the like, consisting of the combination with a door, of a rock-shaft located at one side of a car-track and provided with an arm 19 to be engaged by an approaching car, and a second arm 20, a rod connected with said second arm at one end, a lever to which said rod is connected at the other end, a second rod connected with said lever and with a door to be opened, and a locking device arranged to be operated by an approaching car and serving to hold the door in opened position while the car or train of cars is passing.

4. An automatic door-opening mechanism for mines and the like, consisting of the combination with a door, of a rock-shaft located at one side of a car-track and provided with an arm 19 to be engaged by an approaching car, and a second arm 20, a rod connected with said second arm at one end, a lever to which said rod is connected at the other end, a second rod connected with said lever and with a door to be opened, and a locking device arranged to be operated by an approaching car and serving to hold the door in opened position while the car or train of cars is passing, said locking device comprising an oscillating frame having an arm or projection to be engaged by some part of the car-truck.

5. An automatic door-opening mechanism for mines and the like, consisting of the combination with a door, of a rock-shaft located at one side of a car-track and provided with an arm to be engaged by an approaching car, and with a second arm, and connections between said second arm and the door to be opened comprising a spring which will yield when the first-named arm is struck by the approaching car, to cushion the shock or jar which would otherwise result.

In testimony whereof I affix my signature in presence of two witnesses.

ALFRED C. URBAN.
